[57] CLAIM

The ornamental design for a carrying case for wine bottles and glasses, as shown and described.

DESCRIPTION

FIG. 1 is a perspective view of a carrying case for wine bottles and glasses showing my new design.

FIG. 2 is a side elevational view thereof, the opposite side elevational view being substantially identical thereto;

FIG. 3 is a top plan view thereof;

FIG. 4 is a bottom plan view thereof;

FIG. 5 is an elevational view of one end of the carrying case for wine bottles and glasses, the opposite end elevational view being substantially identical thereto; and FIG. 6 is a perspective view of the carrying case for wine bottles and glasses in open position.
